UNITED STATES PATENT OFFICE.

JULES WEIRICH, OF BÉZIERS, HÉRAULT, FRANCE.

AMALGAMATOR.

SPECIFICATION forming part of Letters Patent No. 377,590, dated February 7, 1888.

Application filed December 8, 1885. Serial No. 185,066. (No model.) Patented in France October 19, 1885, No. 171,735; in England October 27, 1885, No. 12,909; in Brazil January 23, 1886, No. 313; in Canada February 10, 1886, No. 23,391; in India February 12, 1886, No. 19; in Victoria February 19, 1886, No. 4,437; in Italy March 2, 1886, No. 19,319; in New Zealand March 8, 1886, No. 1,741; in Venezuela March 27, 1886; in Austria-Hungary May 1, 1886, No. 41,041 and No. 16,108, and in New South Wales May 3, 1886, No. 1,816.

To all whom it may concern:

Be it known that I, JULES WEIRICH, a citizen of France, residing at Béziers, in the Department of Hérault, have invented certain new and useful Improvements in Amalgamators, (for which Letters Patent have been granted in Great Britain, No. 12,909, dated October 27, 1885; in France, No. 171,735, dated October 19, 1885; in Italy, No. 19,319, dated 5 March 2, 1886; in Brazil, No. 313, dated January 23, 1886; in Venezuela, dated March 27, 1886, (no number;) in Austria-Hungary, No. 41,041 and No. 16,108, dated May 1, 1886; in India, No. 19, dated February 12, 1886; in Victoria, No. 4,437, dated February 19, 1886; in New South Wales, No. 1,816, dated May 3, 1886; in Canada, No. 23,391, dated February 10, 1886, and in New Zealand, No. 1,741, March 8, 1886;) and I do hereby declare the following 10 to be a full, clear, and exact description of the invention, such as will enable others skilled in the art to which it appertains to make and use the same, reference being had to the accompanying drawings, and to letters or figures 15 of reference marked thereon, which form a part of this specification.

This invention relates to certain new and useful improvements in amalgamators, and although especially designed for the recovery 20 of precious metals from the refuse or tailings of mines, to which I will confine the description, yet it will be obvious that said apparatus may be employed for the extraction of such metals from their ores.

The object of this invention is to provide a 25 simple apparatus for recovering, if not all, at least the greater proportion of the precious metals contained in the tailings or residues of mines.

The invention consists in the construction, arrangement, and combination of parts constituting the improved amalgamator, hereinafter fully described, and pointed out in the claims.

In the accompanying drawings, Figure 1 is 30 an end elevation of an amalgamator embodying my invention. Fig. 2 is a top plan view thereof; and Fig. 3, a section taken on line α of Fig. 2, the shaft C being shown in full lines and the agitator removed.

In the recovery of precious metals from tailings I proceed as follows: The tailings are first reduced to a very fine powder, in some cases so fine that they will pass through a silk bolting-cloth having a mesh of No. 100 or No. 120. This reduction may be effected in any suitable apparatus or by any suitable agency—as, for instance, in a grinding or a stamp mill—or by passing the tailings through a "Carr" or "Vappart" machine, or any other analogous machine, apparatus, or means whereby the material may be reduced to the proper degree of fineness. The ground material is classified according to the degree of fineness, and such as is not of the required fineness is returned to the reducing apparatus. The tailings may be 40 ground in a dry or wet state, and the classification may be effected by dry sifting or by gravity in water in a succession of settling-tanks. In the latter process care should, however, be had that the particles of precious metal or metals are not carried out of the settling-tanks when the water is drawn off.

The difficulty of preventing loss of the precious metals in the latter process of classification is well known, and for this reason I prefer to classify the reduced material in a dry condition by passing the same through suitable bolts operated mechanically or otherwise.

The classification, according to the density of the particles of reduced tailings, is effected 50 during the agitation of the same in a bath of water, (or an acidulated bath, according to the nature of the tailings,) which contains a quantity of mercury equal to one thousand or two thousand times the weight of the precious 55 metal or metals combined with such tailings.

The amalgamator shown in the drawings consists, essentially, of a semi-cylindrical pan, B, supported from any suitable frame or support, of wood or masonry or metal, of proper strength to carry the weight and contents of the pan, and its stirring mechanism. In suitable bearings secured to the pan B or its support is mounted a rock-shaft, C, on a line with the longitudinal axis of the pan B and above the same, the said pan being arranged so that its bottom will be perfectly horizontal. On shaft C is secured an agitator, E, composed of

an agitator-blade, e , of the form shown in Fig. 1, of a longitudinal girt, e' , and cross and angle braces e^2 e^3 , respectively.

Any suitable material may be employed in the construction of the pan and its stirrer; but, of course, when acid baths are employed metal will not answer. The girt e' has two or more sockets or sleeves, e^4 , for the reception of radial arms e^5 , that are screw-threaded at their outer ends and carry adjusting-nuts F for adjusting the agitator E relatively to the inner surface of the pan.

It is obvious that by the means described a yielding connection is provided for the agitator E , that allows it to move toward or from the shaft within certain limits. This is necessary in order that the agitator may ride over obstructions should, by accident, anything find its way into the pan that would obstruct its operation.

In operation the agitator should be so adjusted that the edge of its blade e will move in frictional contact with the inner surface of the pan. An oscillating or rocking movement is imparted to the agitator through a crank, D , on shaft C , either by hand or otherwise, and the amplitude of the oscillations should be limited by the level of the bath in the pan B , as shown in dotted lines in Fig. 1, and the depth of this bath will vary according to the nature of the material treated and its degree of fineness—say from about 0.60 centimeter to about 1 meter (more or less) in depth.

At one end of the pan B is a vertical gate-way, G , in which operates a gate, H , to which is secured a screw-rod, J , that works in a screw-threaded opening formed in a bearing, K , also secured to the pan or its support, and said screw-rod is operated, by means of a hand-wheel, I , to raise or lower the gate when a portion of the contents of the pan is to be discharged.

The operation of amalgamation is carried out as follows: The mercurial neutral or acid bath is prepared, the quantity of mercury depending upon the percentage of precious metals in the tailings. If the latter contains about one hundred grams to the ton, about one hundred and fifty or two hundred kilograms of mercury per ton will be necessary. The finely-pulverized material is introduced into the bath and the agitator set in operation. The time required for effecting a thorough separation and amalgamation of a ton of such material will depend on its nature—we will, as an example, say about four hours, which, with the time required for charging and discharging the pan, will be about six hours, or four operations for each twenty-four hours, so that in six days twenty-four tons of material may be operated upon, yielding about two thousand four hundred grams of precious metal, of which fully two thousand grams will have been amalgamated with the mercury and can be recovered by distillation. Of course the duration of the process will vary according to the nature of the material operated upon, as stated, and will gener-

ally be from three to six hours. The agitator should be operated slowly, so as to keep the bath in as quiescent a state as possible, and by this uniform and constant agitation the particles of the material are kept in suspension in the bath and tend by gravity as constantly to precipitate. During this repeated agitation and precipitation in a bath comparatively quiescent the density of the particles—i. e., their relative specific gravity—acts as a means for classifying or sorting the material, which classification is perfected and completed as the operation is prolonged. The heavier precious metal or metals, being precipitated first and meeting the strata and little drops of mercury at the bottom of the pan, are amalgamated therewith. When this operation has been continued for such a length of time, according to the material treated, that the operation of amalgamation may be considered as completed, the gate H is gradually lowered by means of the screw-rod J and hand-wheel I , the agitation of the bath being at the same time kept up and a stream of water allowed to flow into the pan.

It will be observed that the "agitator," so called, although it keeps up a very slight agitation of the bath during its operation, said agitation is simply the sequence of its function, which is not to agitate the bath to any extent, but to continuously change the molecular relations of the mercury, so as to continuously present fresh surfaces to the subsiding metals. The function of the agitator is therefore intended to be primarily that of a spreader and incidentally that of an agitator, since but a very slight agitation is required to hold in suspension mineral matter reduced to the state of subdivision referred to. To this end I provide the agitator with a blade that is rectangular in cross-section and so arrange the blade that it will present one of its angles to the inner surfaces of the pan. The blade e of the agitator E therefore presents two inclined surfaces to the mercury, and as said blade moves almost in contact with the bottom of the pan the mercury is thereby spread over the surface of the pan, thus accomplishing the purposes sought.

The mineral matter held in suspension in the bath may be conducted into settling tanks if such matter has any intrinsic value and it is desired to utilize it.

The gate should not be lowered sufficiently to allow any of the mercury and amalgam to escape, and to prevent the accidental discharge of mercury and amalgam the discharge-opening does not extend quite into the lowest point of the interior of the pan.

Instead of the provisions described for discharging a portion of the contents of the pan, its end wall may be provided with a series of tap-holes at different elevations from the lowest point of the interior of the pan, as will be readily understood, or the partial discharge may be effected by means of siphons or in any other desired manner.

When the operation of discharging is completed, there will remain in the pan the mercury, the amalgam, and a very small proportion of the heavier particles of mineral matter. 5 The discharge-opening of the pan is now closed and the stream of water, when the pan has been filled to the required level, cut off and a fresh charge of finely-pulverized tailings introduced, and these tailings may, if desired, to be roasted either prior to their pulverization, or afterward, as may be found most convenient.

A single charge of mercury will usually be sufficient for several charges of tailings.

When a sufficient quantity of amalgam has 15 been obtained, and after the last charge of refuse has been drawn off, as above explained, the plug K in the end of the pan opposite to the gate H is withdrawn and the amalgam and mercury allowed to run off into a suitable receiver.

The final washing is effected in the usual well-known manner to free the mercury and amalgam from mineral matter, and the precious metal or metals are separated from the 25 mercury by distillation in a close retort, the mercury being recovered in the well-known way for further use.

Having now described my invention, what I claim is—

1. In an amalgamator, the combination, with 30 a semi-cylindrical pan, of a spreader having an oscillating movement, and provided with a blade of rectangular form in cross-section arranged to present one of its angles to the inner surface of the pan, and a crank on the spreader-shaft for oscillating the spreader, substantially as and for the purpose specified.

2. In an amalgamator, the combination, with 35 a semi-cylindrical pan, of a rock-shaft, means, such as described, for imparting to said shaft 40 a rocking motion, a spreader provided with a blade of substantially rectangular form in cross-section arranged to present one of its angles to the inner surface of the pan, and a yielding connection between the spreader and its rock-shaft, substantially as and for the purpose specified.

In testimony whereof I affix my signature in presence of two witnesses.

JULES WEIRICH.
